UNITED STATES PATENT OFFICE.

PETER A. JORDAN, OF PHILADELPHIA, PENNSYLVANIA, ASSIGNOR TO
MACKELLAR, SMITHS & JORDAN, OF SAME PLACE.

DESIGN FOR PRINTING-TYPES.

Specification forming part of Design No. 7,778, dated September 29, 1874; application filed September 9, 1874.
[Term of Patent 14 years.]

To all whom it may concern:

Be it known that I, PETER A. JORDAN, (assignor to MACKELLAR, SMITHS & JORDAN,) of the city and county of Philadelphia, Pennsylvania, have invented and produced a new and original design for Printing - Type, of which the following is a specification:

The nature of my invention is clearly and fully shown in the accompanying typographic impression, to which reference is made; and

consists of a sloping black letter shaded, as clearly shown therein.

What I claim as new is—

The design for a font of printing-types, as herein shown.

P. A. JORDAN.
